UNITED STATES PATENT OFFICE

95,486

DESIGN FOR A COMBINED LAMP AND CLOCK CASE

Clem L. Connally, Fort Worth, Tex.

Application September 17, 1934, Serial No. 53,312

Term of patent 7 years

To all whom it may concern:

Be it known that I, Clem L. Connally, a citizen of the United States, residing at Fort Worth, in the county of Tarrant, the State of Texas, have invented a new, original, and ornamental Design for Combined Lamp and Clock Case, of which the following is a specification, reference being had to the accompanying drawing, forming part thereof.

I claim:

The ornamental design for a combined lamp and clock case substantially as shown.

CLEM L. CONNALLY.
